UNITED STATES PATENT OFFICE.

ALLEN A. ANDERSON, OF CHICAGO, ILLINOIS.

NEEDLE-THREADING THIMBLE.

1,220,387.

Specification of Letters Patent. Patented Mar. 27, 1917.

Application filed February 10, 1915. Serial No. 7,219.

To all whom it may concern:

Be it known that I, ALLEN A. ANDERSON, a citizen of the United States, and a resident of the city of Chicago, in the county of 5 Cook and State of Illinois, have invented certain new and useful Improvements in Needle-Threading Thimbles; and I do hereby declare that the following is a full, clear, and exact description of the same, reference 10 being had to the accompanying drawings, and to the numerals of reference marked thereon, which form a part of this specification.

This invention relates to an improved 15 means associated with a thimble for threading a needle mechanically with any number of strands of thread desired. The mechanism in this invention is so associated with the thimble that no inconvenience is caused 20 to a person wearing the thimble upon a finger, and furthermore there is no possibility of the needle threading mechanism interfering with the work or becoming caught or tangled in the fabric.

25 It is an object therefore of this invention to construct a thimble equipped with a needle threading device which is simple and practical in design and efficient in operation.

30 It is also an important object of this invention to construct a thimble which, on one wall, is creased or grooved inwardly to afford recesses in which a stiff wire hook is 35 mounted, adapted to receive a needle threaded thereon, so that after engagement of the thread in said hook the needle may be removed and mechanically drawn over the thread engaged on said hook, thus threading the needle.

40 It is furthermore an important object of this invention to construct a combination thimble and needle threading device where- 45 in a needle threading mechanism is mounted in a recess provided in the thimble in a manner to permit a thread to be engaged thereon after a needle has been inserted over said mechanism, so that removal of the needle from said mechanism causes the needle to be drawn over the thread, thus thread- 50 ing the needle.

55 It is finally an object of this invention to construct a simple, compact, easily operated needle threading device which is associated with a thimble, permitting convenient application thereof for the purpose of thread-

ing a needle without removing the thimble from the finger.

The invention (in a preferred form) is illustrated in the drawings and hereinafter more fully described.

60

In the drawings:

Figure 1 is a front elevation of a needle threading thimble embodying the principles of my invention.

Fig. 2 is a side view thereof partly broken 65 away and shown in section.

Fig. 3 is a front view similar to Fig. 1, but partly broken away.

Fig. 4 is a fragmentary enlarged sectional detail of one of the walls with the needle 70 threading mechanism mounted therein showing the needle being inserted thereon in the first operation for threading the same.

Fig. 5 is a fragmentary front face view of the part of the thimble shown in Fig. 4, 75 showing the thread being manipulated into place in the second operation of threading the needle.

Fig. 6 is a view similar to Fig. 4, illustrating the third operation of the device in 80 threading the needle.

Fig. 7 is a detail section taken on line 7—7 of Fig. 1.

Fig. 8 is a fragmentary detail of the 85 threading mechanism detached from the thimble.

As shown in the drawings:

The reference numeral 1, indicates as a whole a thimble provided with a lower rolled or beaded edge 2. On one side on the 90 exterior wall of said thimble, the metal is creased inwardly, forming one horizontal and one vertical groove at right angles to one another, as clearly shown in Figs. 1 and 5, and denoted by the reference numerals 95 3 and 4, respectively. Mounted in the vertical groove 4, which may be termed the needle groove, and secured at its lower end, is a relatively stiff fine wire hook member 5, the hooked extremity of which terminates 100 substantially in line with the axis of the horizontal groove 3, which may be termed the thread groove, as clearly shown in Figs. 4, 5, and 6. In threading the needle, which is indicated by the reference numeral 6, 105 the eye thereof is first inserted over the upper looped or hooked end of the member 5, as shown in Fig. 4, and moved downwardly thereon into the position shown in dotted lines. After the needle has been so placed 110

upon the member 5, the thread, which is indicated by the reference numeral 7, is laid in the thread groove 3, so as to engage beneath the hooked extremity of the member 5, and is then brought upwardly on each side into the dotted line position shown in Fig. 5.

The needle then is moved from the dotted line position shown in Fig. 4, upwardly into 10 the dotted line position shown in Fig. 6, thus being drawn over the thread 7, after which of course the thread may be detached from the hook member 5. In the construction illustrated in Fig. 8, I have shown the 15 hook member 5; associated with an integral wire ring 8, which may be sprung into the beaded extremity 2, of the thimble to hold the hook member in proper position. However, it is obvious that the hook member 5, 20 may be secured in its recess in the wall of the thimble in any suitable manner.

The operation is thought to be obvious from the description. However, it is apparent that my device is capable of many 25 variations in form and construction without

departing from the principles thereof, and I therefore do not purpose limiting the patent granted otherwise than necessitated by the prior art.

I claim as my invention:

In a device of the class described, a thimble having needle and thread grooves at a right angle to one another in the outer wall thereof, and a looped needle-threading member mounted in one of said grooves below the outer surface of said thimble, said member having the extremity of its loop terminating in line with the other of said grooves, thus permitting a needle to be engaged thereover and to be drawn therefrom 40 and over a thread which has been passed through the looped extremity of said member.

In testimony whereof I have hereunto subscribed my name in the presence of two 45 subscribing witnesses.

ALLEN A. ANDERSON.
